U.S. Cl. Plt.—81

1 Claim

This invention relates to a new and distinct variety of chrysanthemum plant which is a sport of Escapade, an unpatented but commercial variety.

This sport was selected from a flowering in my commercial greenhouses in Mountain View, Calif., because of its improved dark color, as compared to Escapade. The plant was revegetated and through repeated flowerings the growth proved to be three to five inches shorter than Escapade with a response bloom time of three to five days earlier. At the time of maturity, when the first flowers were cut it was possible to cut fifty percent of the darker sport as opposed to only five percent of the Escapade, which results in all of the dark sport being cut three to five days with twenty-five percent of the Escapade still remaining.

This new sport is similar to Escapade in the following characteristics:

1. Foliage shape
2. Size of Flower
3. Heavy stem and growth

25

30

2

Asexual reproduction of my new and distinct variety has proven to be consistent in:

1. Vegetative growth
- 5 2. Claims of flower characteristics

The overall growth characteristics may vary according to environmental conditions under which it is grown, however, here in the Bay Area of California it has a 10 response period of approximately 7½ weeks and is suggested for year round production.

The accompanying drawing illustrates the color as being as true as possible with color illustrations of this type. The upper flower shows the new variety whereas the lower 15 flower shows a comparison of the new variety on the top with Escapade on the bottom. The color of the new variety will be apparent in the photograph.

The color designation is by use of the Royal Horticulture Society color chart, R. F. Wilson, of the Royal 20 Horticulture Society of London, England.

Plant:

Botanical classification.—*Chrysanthemum morifolium* Ramat.

Origin.—Selected from commercial flowering.

Form.—Herbaceous.

Height.—36-40".

Growth.—Strong vigorous; upright.

	Dark Pinnacle	Escapade	Promenade
Leaf:			
Size	16.2 cm. x 10 cm. (avg.)	16.2 cm. x 10 cm. (avg.)	16.2 cm. x 10 cm. (avg.)
Shape	Ovate, deeply lobed	Ovate, deeply lobed	Ovate, deeply lobed
Texture	Smooth, finely pubescent	Smooth, finely pubescent	Smooth, finely pubescent
Ribs and veins	Prominent	Prominent	Prominent
Margin	Deeply lobed	Deeply lobed	Deeply lobed
Color	Yellow green 147/A	Yellow green 147/A	Green 139/A
Bud:			
Diameter	3.4 cm.	3.5 cm.	3.2 cm.
Depth	2.5 cm.	2.3 cm.	2.3 cm.
Color	Red purple 74/D	Red purple 65/C	Red purple 65/C
Flower color:			
Center of flower	Red purple 73/D	Red purple 65/D	Red purple 65/D
Base of petal (1/4" from end)	Red purple 74/D	Red purple 73/C	Red purple 68/C
Inside of petal	Red purple 74/B	Red purple 74/D	Red purple 74/D
Reverse of petal	Purple 75/C	Purple 75/C	Purple 75/C
Tonality from distance	Red purple 74/C	Red purple 65/B	Red purple 73/B
Other characteristics:			
Size of flower	13.5 cm. x 8.84 cm.	13.4 cm. x 8.95 cm.	13.5 cm. x 6.25 cm.
Stamens	Numerous	Few	None
Pollen	None visible	None visible	Do.
Pistil	Present	Present	Present

This new selection is different from Escapade in the following ways:

1. Intense and darker color
2. Three to five inches shorter plant growth
3. Less bruising
4. Resistance to fading
5. Three to five days earlier flower response
6. Lower percentage of culs

50 I claim:

A new and distinct variety of chrysanthemum having the characteristics of a darker flower, three to five days earlier flower response; three to five inches shorter mature growth; and numerous stamens present, which characteristics show a distinct difference over Escapade and 55 Promenade.
